UNITED STATES PATENT OFFICE.

OSCAR A. ERICSON, OF CHICAGO, ILLINOIS, ASSIGNOR TO W. W. KIMBALL COMPANY, OF CHICAGO, ILLINOIS, A CORPORATION OF ILLINOIS.

DOUBLE-ACTING PNEUMATIC MOTOR.

Application filed July 31, 1920. Serial No. 400,467.

To all whom it may concern:

Be it known that I, OSCAR A. ERICSON, a citizen of the United States, residing at Chicago, in the county of Cook and State of Illinois, have invented certain new and useful Improvements in Double-Acting Pneumatic Motors, of which the following is a specification.

This invention relates to an improved double acting motor for use in self-playing musical instruments, and has been designed more especially, although not exclusively, as a device to effect automatic actuation of music sheet guides or tracker devices as they 15 are commonly known in the art.

In order that my invention will be clearly understood both as to its structure and as to its peculiar utility as a motor for music sheet guides or trackers I have illustrated 20 the same in the accompanying drawings in connection with a tracker device, and referring thereto—

Fig. 1 is a front elevation of the tracker-range or bar, music sheet and spools and the 25 mounting devices of the latter, and showing my improved pneumatic motor applied thereto;

Fig. 2 is a top plan view, partly broken out and in section, of the parts shown in 30 Fig. 1;

Fig. 3 is a vertical section through the pneumatic motor, taken on the line 3—3 of Fig. 1; and

Fig. 4 is a vertical section taken on the 35 line 4—4 of Fig. 3.

Referring to the drawings, 5 designates as a whole a rectangular frame, in the vertical sides of which are journaled endwise movable chucks 6 and 7 which support the upper or delivery roll 8, and similar chucks 9 and 10 which support the lower or receiving roll 11. 12 designates the perforated music web or sheet extending between the rolls 8 and 11 and traveling over the tracker-range or bar 13. The chuck 6 has a spindle 6' the outer end of which is slidably mounted in a bracket 14 secured to one vertical side member of the frame 5, said chuck and spindle being urged inwardly by a coil 40 spring 15 abutting at its outer end against the bracket 14 and at its inner end against a collar 16 keyed on the spindle 6'. The chuck 7 has a spindle 7' slidably mounted in a bracket 17 secured to the opposite vertical member of the frame 5 and carrying a

re-winding sprocket 18. The chuck 9 of the lower roll has a spindle 9' slidably mounted in a bracket 19 secured to the frame 5 and normally urged inwardly by a coil spring 20 abutting at its outer end against the bracket 19 and at its inner end against a collar 21 keyed on the spindle 9'. The opposite chuck 10 likewise has a spindle 10', the outer end of which is journaled in a bearing 22 on the bracket 17.

Secured to the frame 5 and the bracket 14 is a laterally extending horizontal strip 23, and secured to the bracket 19 is a laterally extending horizontal strip 24. Secured to and supported by the strips 23 and 24 is a 65 double-acting pneumatic motor, the details of which are best shown in Figs. 3 and 4. This motor comprises my improved V-shaped block 25, and a pair of movable below wings 26 and 27 hinged at their upper 70 ends at 28 and 29 respectively to the upper end of the block 25, these wings being equipped with the usual foldable sides 30 and 31, thereby constituting a pair of oppositely acting bellows having a common 75 stationary side in the block 25. In the block 25 is a vertical duct 32, the lower end of which is tapped by a pipe 33 to which is connected a hose 34 leading to the usual exhaust or suction chest of the instrument conventionally indicated at 35 in Fig. 1.

Communicating with the vertical duct 32 is a horizontal duct 36 that extends through the rear side of the block 25, as shown in Fig. 3, and below the same is a similar horizontal duct 37 that likewise communicates with the vertical duct 32 and extends through the rear side of the block 25.

Communicating with and extending at right angles to the duct 36 is a duct 38 (Fig. 95 4) that leads into the right hand pneumatic shown in Figs. 1 and 4, and communicating with and extending at right angles to the duct 37 is a similar duct 39 that leads into the left hand pneumatic shown in Figs. 1 100 and 4. Within the ducts 36 and 37 are located small metal disks 40 and 41 respectively having therein bleed holes 42 and 43. The two pneumatics are thus in constant communication with the exhaust or suction chamber 35 through the ducts and bleed holes described. The pneumatics are held against simultaneous closing and for simultaneous action by bars 44 that are pivotally connected to and between the opposite 105 110

edges of their movable sides 26 and 27 as shown at 45 and 46 in Fig. 1. The bars 44 are preferably slotted, as shown at 47, and ride on guide pins 48 set into the front and 5 rear sides of the block 25. These bars 44 thus cause the movable sides of the pneumatics to act against each other, thereby holding both pneumatics normally open under the suction. Manifestly, if the suction 10 effect in either pneumatic is destroyed, the two movable sides will move in unison in one direction or the other.

The tracker-bar 13 is equipped with the usual row of apertures 13' which, in co-operation with the music sheet, control the striking pneumatics of the player action in a manner well understood in the art. Just opposite the ends of this row of openings 13' are a pair of openings 49 and 50 that, 15 in the normal and correct position of the music sheet 12, are covered by the edges of the latter. From the opening 49 at the left or bass end of the tracker-bar extends a tube 51 (Fig. 2) which leads to and communicates with a pipe 52 (Fig. 3) that is entered into the duct 37 through the rear wall of the block 25; and communicating with the opening 50 at the right or treble end of the tracker-bar is a similar tube 53 that leads 20 to and communicates with a pipe 54 that enters the duct 36 through the rear wall of the block 25. Hence, if the opening 49 be uncovered by the music-sheet atmospheric air will enter through the tube 51, pipe 52, 25 and ducts 37 and 39 into the left hand pneumatic shown in Figs. 1 and 4, whereupon the movable sides of both pneumatics will swing to the left under the suction in the right hand pneumatic, as shown by dotted lines in 30 Fig. 1. If the opening 50 at the right hand end of the tracker-bar be uncovered, atmospheric air will flow through the tube 53, pipe 54 and ducts 36 and 38 into the right hand pneumatic shown in Figs. 1 and 4, 35 whereupon the movable sides of both pneumatics will swing to the right as shown by dotted lines in Fig. 1.

The motor operates the upper or delivery roll 8 to shift the latter endwise by the following mechanism.

Connecting the movable sides 26 and 27 of the motor near their upper ends and on the back or reverse side is a bar 55 (Fig. 2) to the center of which is pivotally connected at 55 56 an actuating rod or bar 57 extending behind the frame 5 of the upper roll 8 and slidably mounted in a bearing block 58 on the rear side of the frame 5, the rod extending some distance beyond the frame 5. 60 Fastened on the free end of the rod 57 is a forwardly extending arm 59 carrying at its free end a disk 60 that normally abuts against the outer end of the chuck spindle 7'. Keyed on the rod 57 is a collar 61, and between this collar and the bearing block 58

is a coiled compression spring 62. The springs 15 and 62 are both under a light compression and act oppositely upon the roller 8, the spring 15 tending to shift said roller to the right, and the spring 62 tending to shift said roller to the left. In the normal and correct position of the roller the two springs just balance or neutralize each other.

In the operation of the mechanism, so 75 long as the music sheet remains in correct registration with the tracker-bar, both holes 49 and 50 are covered, and the motor is held idle or inactive in the position shown by full lines in Fig. 1. If the sheet creeps toward the right, the hole 49 is partly uncovered, the vacuum existing in the left hand pneumatic is broken, and the movable sides of the two pneumatics swing in unison to the left, as indicated by dotted lines in Fig. 80 1. This, through the rod 57, arm 59, and disk 60, instantly shifts the roll 8 slightly to the left so that the music sheet instantly resumes its normal and correct position on the tracker-bar. If the music sheet creeps toward the left, the hole 50 is uncovered sufficiently to admit atmospheric air to the tube 52, which breaks the vacuum in the right hand pneumatic, causing the movable sides of the pneumatic to swing toward the right. 85 This, through the rod 57 and collar 61, compresses the spring 62 and shifts the arm 59 and disk 60 away from the end of the chuck spindle 7', so that the spring 15 is then free to shift the roll 8 to the right until the hole 50 is fully covered, thus restoring the normal and correct registration of the sheet with the tracker-bar. When the holes 49 and 50 are both covered by the sheet, the 90 exhaust acting through the tube 34 maintains both of the motor pneumatics in normal condition wherein they are both under vacuum, and assume the balanced position 95 shown by full lines in Fig. 1.

From the foregoing it will be seen that 100 the motor acts to positively shift the roll 8 in one direction, overcoming the opposed and balanced action of the springs 15 and 62; while the spring 15 constitutes the active agent in shifting the roll 8 in the opposite 105 direction when relieved by the motor of the opposition of the spring 62. This automatic shifting action is very sensitive and rapid, occurring upon the slightest partial uncovering of either of the holes 49 and 50, and 110 instantly restoring the music sheet to normal and correct registration before it has moved far enough to produce any discord in the music rendered by the instrument.

I claim:

1. A double acting pneumatic motor for music sheet tracker devices, comprising a stationary central block and a pair of bellows having movable sides hinged to opposite sides of said block, a main suction duct 115

125

130

- formed in said block, a suction pipe communicating with said main suction duct, branch ducts in said block leading from said main suction duct into said bellows, respectively, bleed vents in said branch ducts, independent pressure connections leading into said block and communicating with said branch ducts on the opposite sides of said bleed vents from said main suction duct, a 10 music sheet directly opening and closing said pressure connections and a bar connecting and spacing the movable sides of said bellows for simultaneous movement in either direction.
- 15 2. A double acting pneumatic motor for music sheet tracker devices, comprising a stationary V-shaped central block and a pair of bellows having movable sides hinged at their upper ends to opposite sides of the 20 wide end of said block, a main vertical suction duct formed in said block, a suction pipe communicating with said main suction duct, horizontal branch ducts in said block leading from said main suction duct into said bellows, respectively, bleed vents in said branch ducts, independent pressure connections leading into said block and communicating with said branch ducts on the opposite sides of said bleed vents from said main 25
- suction duct, a music sheet directly opening 30 and closing said pressure connections and a bar connecting and spacing the movable sides of said bellows near their lower ends for simultaneous movement in either direction. 35
3. A double acting pneumatic motor for music sheet tracker devices, comprising a stationary central block and a pair of bellows having movable sides hinged at their upper ends to opposite sides of the upper 40 ends of said block, a main suction duct formed in said block, a suction pipe communicating with said main suction duct, branch ducts in said block leading from said main suction duct into said bellows, respectively, bleed vents in said branch ducts, independent pressure connections leading through said block into both of said bellows, a music sheet directly opening and closing 45 said pressure connections, a bar connecting and spacing the movable sides of said bellows near their lower ends for simultaneous movement in either direction, another bar connecting and spacing the movable sides of said bellows near their upper ends, and an 50 actuating rod pivotally connected to said last-named bar. 55

OSCAR A. ERICSON.
